INVENTOR.
Emmet S. Soule,
BY

Geo. P. Kimmel. ATTORNEY.

UNITED STATES PATENT OFFICE.

EMMET S. SOULE, OF SOUTH BEND, WASHINGTON.

HOOK.

Application filed March 28, 1923. Serial No. 628,286.

To all whom it may concern:

Be it known that I, EMMET S. SOULE, a citizen of the United States, residing at South Bend, in the county of Pacific and State of Washington, have invented certain new and useful Improvements in Hooks, of which the following is a specification.

This invention relates to a butt hook designed primarily for use in logging, but it is to be understood that a hook in accordance with this invention can be employed for any purposes for which it is found applicable, and the invention has for its object to provide in a manner as hereinafter set forth, a butt hook including a spring controlled manually releasable locking device associated with a guard for securing the latter in cooperative position with respect to the bill of the hook, to close the latter thereby maintaining the hook in coupled engagement with the article with which it is connected, or rather to prevent the breaking away of the hook, until the guard is released, from the article with which it is attached.

Further objects of the invention are to provide a hook of the class referred to, in the manner as hereinafter set forth, which is simple in its construction and arrangement, strong, durable, compact, readily assembled, thoroughly efficient in its use, conveniently opened and closed when occasion so requires, and inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a side elevation of a hook in accordance with this invention.

Figure 2 is an edge view thereof.

Figure 3 is a fragmentary view, partly in vertical section, and further illustrating the guard, in dotted lines, shifted to inoperative position.

Referring to the drawings in detail, a hook in accordance with this invention comprises a shank 1, formed at one side with a

lateral offset 2. The shank 1, near its inner end, is provided with an opening 3 for the purpose of connecting the shank 1, to a line, chain, or other object. The shank 1, has extending from one side of its outer end the body portion 4 of the hook, and said body portion 4 is curvilinear in contour and terminates in a bill 5, which is spaced from the lateral offset 2 of the shank and which has its free terminus beveled, as at 6, and medially of the bill 5, at its free terminus, the bill 5 is formed with a lug 7, having a beveled end 8.

The lateral offset 2 of the shank is provided with an inclined pocket formed of two different diameters, and that portion of smaller diameter of the pocket is indicated at 9, and the portion of larger diameter at 10. The pocket opens at the outer end of the shank, is disposed at an outward inclination and is arranged whereby it will open outwardly with respect to the lug 7 of the bill 5. Arranged in the reduced portion 9 of the pocket is a coiled spring 11, which abuts against the head 12, carried on the inner end of the shank 13 of a spring controlled locking member. Mounted against the shoulder 14, formed at the joinder of the reduced portion 9 with the enlarged portion 10 of the pocket, is a washer 15, against which abuts the head 12 of the locking member. The shank 13 extends through the washer 15.

A part of the wall of the portion 10 of larger diameter of the pocket is threaded and engaging with said threaded wall is a peripherally threaded holding member 16 formed with a central bore 17, through which extends the shank 13 of the locking member.

The shank 13 permanently extends through the washer 15 and locking member 16 and is of such length as to project from said holding member, for a purpose to be presently referred to. The spring 11, bearing against the head 12, normally maintains the shank 13 in its projected position. The locking member is shifted inwardly manually, against the action of the spring 11, so that when pressure is released from said locking member, the spring 11 will automatically shift the same outwardly, so that the shank 13 will be projected from the holding member 16.

The hook includes a pivoted guard with which the spring controlled locking member

associates for the purpose of securing said guard in cooperative relation with respect to the bill 5, to close the hook, thereby maintaining the latter in coupled engagement 5 with the article to which it is connected, or rather to prevent the breaking away of the hook, unless the guard is released, from the article to which the hook is attached. The said guard consists of a body portion 17, 10 having its outer end bifurcated, as at 18, for the purpose of straddling the lug 7. The outer end of the body portion 17 is beveled as at 19, and when the body portion is in position, as shown in Figure 1, to close the 15 hook, the said beveled end 19 opposes the beveled end 6 of the bill 5. Formed integral with the inner end of the body portion 17 is a pair of arms 20, between which extends the offset portion 2 of the shank 1. 20 The arms 20 are pivotally connected to the offset portion 2, by the pin 21, which extends through the arms 20 and also the offset portion 2.

The body portion 17 is flaring from its 25 outer towards its inner end and the sides thereof form a continuation of the sides of the bill 5. The arms 20 are of greater width than the width of the body portion 17.

The body portion 17 is formed with a 30 lengthwise groove 22, at its inner end, forming a clearance for the outer end of the shank 13 and also whereby the said outer end of the shank 13 is protected by the guard. The groove 22 is formed in the 35 guard at the outer side thereof and provides means whereby access can be had to the locking member to release the same.

The holding member 16 is detachable so 40 that it can be removed when occasion requires and a new locking member substituted if the locking member becomes damaged or broken, or to substitute a new spring 11 if desired. The locking member is shifted manually inwardly when it is desired to release the guard or shift the guard 45 to close the hook.

Although the preferred embodiment of 50 construction of butt hook is as shown and described, yet it is obvious that changes in the details of construction can be had which will fall within the light of the invention as claimed.

What I claim is:

1. A hook comprising a shank formed 55 with a lateral offset at one side, a body portion extending from the other end of said shank at one side thereof and terminating in a bill having a centrally disposed lug projecting therefrom, a guard overlapping 60 and projecting from and further pivotally connected at one end to the lateral offset of the shank and having its free end bifurcated for the reception of said lug, and a spring controlled manually releasable lock- 65 ing device carried by the lateral offset por-

tion of the shank and extending into and cooperating with said guard for maintaining it in overlapping position with respect to said lug to close the body portion of the hook.

2. A hook comprising a shank formed 70 with a lateral offset, a body portion extending from one end of said shank at one side thereof and terminating in a bill having a lug projecting therefrom, a guard pivotally connected at one end to the lateral offset of 75 the shank, said guard projecting from the shank and its free end bifurcated for the reception of said lug, and a spring controlled manually releasable locking device carried by the lateral offset portion of the shank and 80 cooperating with said guard for maintaining it in overlapping position with respect to said lug to close the body portion of the hook, said guard having its outer side edge 85 provided with a groove for the reception of the outer end of the locking device when the latter maintains the guard in position to close the body portion.

3. A hook comprising a shank, a body portion projecting therefrom and terminating in a bill, a guard pivotally connected at one end to the shank, said guard extending from said shank and having its free end cooperating with said bill to close the body portion, and a spring controlled and 90 manually releasable locking device carried by the shank and cooperating with said guard for maintaining it in position to close the body portion, said guard having its outer side edge 95 provided with a groove for the reception of the outer end of the locking device when the latter maintains the guard in position to close the body portion.

4. A hook comprising a shank, a body portion projecting therefrom and terminating in a bill, a guard pivotally connected at one end to the shank, said guard projecting from the shank and having its free end cooperating with said bill to close the body portion, and a spring controlled and 100 manually releasable locking device carried by the shank and extending in and cooperating with said guard for maintaining it in position to close the body portion, and said locking device including removable means for detachably connecting it with the shank. 110

5. A hook comprising a shank, a body portion projecting therefrom and terminating in a bill, a guard pivotally connected to the shank and cooperating with said bill to close the body portion, and a spring controlled and 115 manually releasable locking device carried by the shank and extending in and cooperating with said guard for maintaining it in position to close the body portion, said guard having its outer side edge 120 provided with a groove for the reception of the outer end of the locking device when the latter maintains the guard in position to close the body portion, and said locking device in- 125

cluding removable means for detachably connecting it with the shank.

6. A hook comprising a body portion provided with a pocket opening at one end thereof, a body portion projecting from said shank and terminating in a bill extending towards the open end of the pocket, a guard pivotally connected to said shank, projecting therefrom and cooperating with said bill to close the body portion, a coiled spring mounted in said pocket, a headed

locking member bearing against said spring, and means detachably engaging with said shank for connecting said locking member therewith, said locking member removably extending into the outer side edge of said guard for maintaining the latter in position to close the body portion. 15

In testimony whereof I affix my signature hereto.

EMMET S. SOULE.
